CLAIM

The ornamental design for a mast cradle for a catamaran sailboat, as shown and described.

DESCRIPTION

FIG. 1 is a perspective view of a mast cradle for a catamaran sailboat showing my new design;

FIG. 2 is a top plan view thereof;

FIG. 3 is a bottom plan view thereof;

FIG. 4 is a front end elevational view thereof;

FIG. 5 is a rear end elevational view thereof; and,

FIG. 6 is a reduced side elevational view thereof, the opposite side, elevational view being a mirror image of that shown.

FIG. 2

FIG. 3

FIG. 4

FIG. 6

FIG. 5
